Inventor:

Thomas H. Neal

THOMAS H. NEAL, OF ALLEGHENY, PENNSYLVANIA.

Letters Patent No. 91,154, dated June 8, 1869.

IMPROVEMENT IN ATTACHING HANDLES TO PICKS.

The Schedule referred to in these Letters Patent and making part of the same.

To all whom it may concern:

Be it known that I, THOMAS H. NEAL, of the city and county of Allegheny, in the State of Pennsylvania, have invented a new and useful Improvement in "Mining-Picks;" and I do hereby declare that the following is a full and exact description thereof, reference being had to the accompanying drawings, and to the letters of reference marked thereon.

The nature of my invention consists in providing a mining-pick with a holder or handle-socket, and a clamping-screw, the several parts being constructed and arranged, with relation to each other, in the manner hereinafter described.

To enable others skilled in the art to make and use my invention, I will proceed to describe its construction and operation.

In the accompanying drawings, which form part of my specification—

Figure 1 is a side view of the pick and its holder or socket, representing the pick and socket secured to a section of a pick-handle.

Figure 2 is a side view of the pick-holder or socket, provided with a section of handle and pick.

Figure 3 is a longitudinal section of fig. 2.

In the drawings, A represents the pick, which is made from a square bar of steel, which is pointed and "tempered."

At the centre, where it is held in the holder or socket, it is provided with a notch or recess, x.

The holder or socket B is made of cast-brass, and

may be made of malleable cast-iron, or other suitable material.

In the part marked e, of the holder or socket B, is placed a clamping-screw, C, for the purpose of holding the pick A in a fixed position in the holder or socket B.

The handle D is made of wood, and may be secured in the holder or socket B, through the medium of a wedge or other device.

To remove the pick A out of the holder or socket B, it is only necessary to slacken up the clamping-screw C; and to secure the pick in its holder or socket, it is placed in the holder or socket, as shown in fig. 3, and the clamping-screw forced firmly against the pick.

The advantage of my improvement consists in cheapness of construction, and the facility and security with which the several parts may be adjusted and secured together.

I do not claim broadly a mining pick, made in several parts, for such device is well known.

Having thus described the nature, construction, and operation of my improvement,

What I claim as of my invention, is—

The pick-holder B, and clamping-screw C, when constructed and arranged substantially as herein described, and for the purpose set forth.

THOMAS H. NEAL.
